Primary Examiner — Cynthia Ramirez*Assistant Examiner* — Llorellys Martinez-Rivera(74) *Attorney, Agent, or Firm* — Husch Blackwell LLP(57) **CLAIM**

The ornamental design for a bezel for a ring, as shown and described.

DESCRIPTION

FIG. 1 is a perspective view of a bezel for a ring showing our new design;

FIG. 2 is an enlarged view thereof;

FIG. 3 is a top plan view thereof;

FIG. 4 is a front elevation view thereof;

FIG. 5 is a right side elevation view thereof;

FIG. 6 is another enlarged view thereof;

FIG. 7 is a left side elevation view thereof;

FIG. 8 is another enlarged view thereof; and,

FIG. 9 is a rear elevation view thereof.

The broken lines shown in the drawings illustrate environmental subject matter and form no part of the claimed design.
